UNITED STATES PATENT OFFICE.

JOHN B. OLSON, OF FORT ATKINSON, WISCONSIN, ASSIGNOR TO JAMES MANUFACTURING CO., OF FORT ATKINSON, WISCONSIN.

CHICKEN FEEDER.

Application filed October 23, 1922. Serial No. 596,239.

My invention relates to improvements in chicken feeders.

The primary object of my invention is to provide a sanitary feeder which will substantially eliminate waste.

A further object of my invention is to provide means whereby chickens will be compelled to leave the floor of the coop in order to obtain access to the feed, and whereby they will be required to stand in a specific position with reference to the feed tray while feeding.

A further object of my invention is to provide effective means for preventing the chickens from roosting on the top of the feed containing box or magazine.

In the drawings:

Figure 1 is a perspective view of a chicken feeder embodying my invention.

Figure 2 is a plan view of the same with the top removed.

Figure 3 is a transverse sectional view, Figures 1 and 2.

Figure 4 is a similar sectional view showing a modified form of construction adapted to be connected with the wall of the coop.

Figure 5 is a perspective view of the same.

Like parts are identified by the same reference characters throughout the several views.

As shown in Figures 1, 2, and 3, the magazine of my improved feeder comprises an elongated rectangular magazine 1 supported with its lower margins within a feed pan 2 and having an open bottom as shown in Figure 3. The bottom 3 of the feed pan is preferably provided with a central V-shaped rib formed by the upwardly converging walls 4, this rib being directly underneath the longitudinal center line of the magazine 1. The magazine is supported from the side walls of the pan 2 by a set of web members 6 which preferably fit within the feed pan and rest upon the bottom thereof. These web members 6 subdivide the magazine into compartments 7, 8, and 9, the webs 6 constituting partitions within the magazine and extending beyond its side walls and being provided with upwardly tapering margins 10. The magazine chambers 7, 8, and 9 have their walls provided with inturned flanges 12 which

are bolted or riveted to the partitions as clearly shown in Figure 2.

The feed pan is supported in a raised position and at a substantial distance above the floor by legs 13, preferably composed of sheet metal bent to form channelled or angle shaped supports having foot pieces 14 at their lower ends and braces 15 connecting their upper end portions with the feed pan. The legs are connected in pairs by cross bars 16 which extend beyond the feed pan and form supports for the feeding boards 18 upon which the chickens stand when feeding.

The cross bars 16 also provide supports for a set of removable trays having inner walls 21 and end walls 20 adapted to slide underneath the feeding pan 2. The outer walls 22 of these removable trays are extended upwardly to a substantial distance above the outer walls of the feed pan 2 and are provided with inturned flanges 23 and end flanges 24. These walls 22, with the flanges 23 and 24, serve as guards to prevent grain from being thrown by the chickens from the feed pan 2 to the floor of the coop. Substantially all the grain thrown by the chickens from the feed pan 2 will be caught by these walls and directed downwardly into the associated removable tray, the bottom 25 of which rests upon the cross bars 16.

Feed regulating slides 27 are adjustably secured to the side walls of the magazine. 85 The slides are vertically slotted and are connected with the wall of the magazine by screws or bolts 28. These slides are utilized to support a series of guard fingers 30, preferably composed of wire and which 90 extend downwardly and outwardly with their outer extremities resting upon the upper margins of the walls of the feed pan 2, these margins being also provided with in-turned flanges 31 which assist in preventing 95 the chickens from throwing grain from the feed pan 2. The guard fingers 30 are spaced at sufficient distances to allow the chickens to put their heads into the pan, but they are in sufficiently close proximity to prevent the chickens from snapping the grain violently 100 to one side or the other as chickens are apt to do if their feeding movements are unrestrained.

The guards are preferably formed by bending a piece of wire into a generally U-shaped form with the loop hinged to the upper margin of the slide 27, by sliding and bending said upper margin around the middle portion of the loop to form a hinged joint.

To prevent the chickens from roosting on the top of the magazine, the cap of the magazine is formed with upwardly converging walls 35 and 36 and vertical flanges 37 which fit slidably over the top of the magazine in the form of a removable cover. The apex formed by the converging walls 35 and 36 is covered by a plate or piece of sheet metal 40, connected to the cap by bolts or rivets 41 which extend loosely through holes in the plate 40. The upper head of the bolt or rivet 41 limits the tilting movement of the plate 40 while allowing the plate to tip freely in either direction to such an angle that none of the fowls can retain a footing thereon.

The flat surface of the plate and the relatively thin sharp edges thereof prevent the chickens from obtaining a foothold, and after a few attempts to find a roosting place on the top of the magazine they abandon the effort.

Great importance is attached to the removable tray for catching and retaining any grain thrown by the chickens from the relatively fixed pan 2. It has been found in practice that during a single day, chambers 44 of the removable tray frequently become from one-third to one-half filled with grain which would otherwise have been thrown to the floor of the coop and largely wasted. The grain collected by these removable trays 44 is clean and may be returned to the magazine by removing the cover or cap and then removing each tray and dumping its contents back into the magazine.

To prevent the chickens from dislodging the removable trays, a resilient stop 46 is preferably employed. This comprises a piece of sheet metal secured to the under surface of the associated feeding board 18, and preferably having its inner margin elbowed to form a downwardly extending flange 47 adapted to bear against the wall 22 of the removable tray near its lower margin.

It will be noted that the magazine chambers 7, 8, and 9 may be utilized to contain different kinds of grain, ground feed, grits, etc. The chambers 8 and 9 are preferably further sub-divided by vertical partitions 50, and the chamber 7 is preferably employed as the main feeding chamber, the smaller chambers serving to receive oyster shell, ground bone, grit, etc. It is, therefore, not necessary to provide removable trays for catching material thrown from the end portions of the feed pan 2 beyond the partition walls 6.

Referring now to Figures 4 and 5, it will be observed that the construction is quite similar to that of the central portion of the feeder shown in Figures 1, 2, and 3. The chamber 57 is similar in purpose to the 70 chamber 7 in Figure 1, but the feeding pan 58 is preferably an integral portion thereof, the lower portion of the chamber 57 having an inclined wall 59 which also constitutes the back wall of the feeding pan, only one pan 75 being provided for the reason that the vertical back wall 60 of the chamber 57 is connected with a supporting wall or member 61 within the coop. It is preferably removably connected with such wall, the latter 80 having screws 62 over the heads of which the feeder may be hung by providing the wall 60 of the feeder with inverted key-hole slots at 63.

The ends 64 of this modified feeder are preferably extended downwardly, and the 85 feed board 18 is supported therefrom by bars 65 riveted to the lower marginal portions of the wall 64. The removable trays 44 are similar to the trays 44 above described, disclosed in Figure 41, and the 90 guard fingers 30 and slide 27 are the same as those shown in Figure 1. The top wall 67 of the magazine preferably comprises a cover hinged to the back wall at 68 and inclined downwardly and forwardly at a sufficient angle to prevent the chickens from 95 roosting on top of the magazine.

I claim:

1. A chicken feeder comprising the combination of a feed pan provided with supporting legs, a superposed magazine adapted to feed material progressively into the pan, a feed board supported from the legs outwardly from the tray, and a removable food catching receptacle positioned between the feed board and the pan and having one wall extending upwardly above the pan at a distance therefrom and constituting a baffle for material thrown from the pan. 100

2. In a chicken feeder, the combination with a relatively fixed feed pan supported at a height above the ground to prevent chickens thereon from taking food from said pan, of a feed board having spaced supporting bars connected with and extending beneath said pan, and a removable food catching receptacle slidably mounted on said supporting bars, said receptacle having a wall spaced from and extending upwardly above said pan to direct material thrown 110 from the pan into the receptacle. 115

3. In a chicken feeder the combination with a supporting frame provided with a raised feed board, a relatively fixed pan connected with the frame, a magazine supported from the frame above said relatively fixed pan and provided with an open bottom, a feed slide adapted to regulate deliveries from the magazine into said pan, a co-operating removable tray adapted to 120 125 130

catch material thrown from the relatively fixed pan and loosely supported by said frame, and a set of guard fingers connected with the feed regulating slide with the outer ends of the fingers supported on the outer margin of the fixed pan and projecting in the direction of the outer wall of the removable tray.

4. In a chicken feeder, a supporting frame, a relatively fixed feed pan, a superposed magazine adapted to deliver material into said pan, a top for said magazine provided with walls which converge upwardly to form a relatively narrow meeting portion, a flat plate arranged in a plane inclined to the vertical loosely connected to said top above said meeting portion and extending laterally at each side of said meeting portion above the upwardly converging walls, said plate being free to tilt to opposite sides of said meeting portion.

5. In a chicken feeder, the combination with a relatively fixed feed pan supported at a height above the ground to prevent chickens thereon from taking food from said pan, of a feed board having spaced supporting bars connected with and extending beneath said pan, a removable food catching receptacle slidably mounted on said supporting bars, said receptacle having a wall spaced from and extending upwardly above said pan, securing means for removably holding said receptacle in food catching position.

6. In a chicken feeder a relatively fixed pan, a removable pan, means for feeding material into the relatively fixed pan, means for supporting the removable pan in a position to catch the material thrown over one wall of the fixed pan, the outer wall of the removable pan extending above the level of the outer wall of the relatively fixed pan and provided with an inturned flange, and perch means outside said outer wall whereby the latter is positioned between the perch means and said fixed pan.

7. In a chicken feeder the combination of a frame having supporting legs, a relatively fixed pan carried thereby, a removable tray adapted to be supported from the frame in a position with one portion extending under the fixed pan and another portion extending upwardly along the side thereof, a feed board supported from the frame outwardly from the removable and fixed pans, and means for preventing fowls from throwing material from the relatively fixed pan over the outer wall of the removable tray.

8. In a chicken feeder the combination of a frame having supporting legs, a relatively fixed pan carried thereby, a removable tray adapted to be supported from the frame in a position with one portion extending under the fixed pan and another portion extending upwardly along the side thereof, a feed board supported from the frame outwardly from

the removable and fixed pans, means for preventing fowls from throwing material from the relatively fixed pan over the outer wall of the removable tray, and a manually operable stop for holding the removable tray in position to catch material thrown over the outer wall of the relatively fixed pan.

9. In a chicken feeder, a feed pan having a relatively fixed means of support above the ground, a feed board associated with said pan, receptacle supporting means extending outwardly beneath said pan, and a food catching receptacle positioned adjacent said pan, said receptacle having a sliding movement on said supporting means to remove the same from said pan, and means for maintaining said receptacle in food catching position adjacent the pan, said means including a resilient stop positioned in the path of said receptacle to prevent sliding movement away from said pan.

10. In a chicken feeder, the combination with a feed pan supported above the ground, of a roost connected with said pan, a food catching receptacle removably and slidably connected with said pan, and a spring latch connected with said roost and provided with a shoulder yieldably interposed in the path of withdrawal of said receptacle, whereby to maintain said receptacle in an operative position for catching food.

11. In a device of the character described, the combination with two pairs of legs, each pair being connected by an upright partition wall extending above said legs, of spaced transversely extending walls connecting said upright walls and providing therewith a central feed compartment, and a set of additional walls disposed exteriorly of each of said upright walls to comprise therewith an end compartment, together with food supporting means carried by said legs beneath said several compartments and operatively arranged to receive material therefrom.

12. In a device of the character described, the combination with two pairs of legs, each pair being connected by an upright partition wall extending above said legs, of spaced transversely extending walls connecting said upright walls and providing therewith a central feed compartment, and a set of additional walls disposed exteriorly of each of said upright walls to comprise therewith an end compartment, together with food supporting means carried by said legs beneath said several compartments and operatively arranged to receive material therefrom, said upright partition walls having downwardly diverging margins extending laterally beyond the lower portions of the others of said walls, whereby to provide lateral braces for said compartments.

13. In a device of the character described, the combination with a feed receiving pan

provided with legs arranged in pairs near the ends thereof, of a set of feed compartments extending longitudinally of said pan and spaced inwardly from either side thereof, braces extending from said legs to said compartments, and partitions in substantial registry with said braces separating the several compartments.

14. In a device of the character described, the combination with a feed receiving pan provided with legs arranged in pairs near the ends thereof, of a set of feed compartments extending longitudinally of said pan and spaced inwardly from either side thereof, braces extending from said legs to said compartments, partitions in substantial registry with said braces separating the several compartments, and guard grates connected with the sides of an intermediate compartment, said guard grates being arranged

to cover portions of said pan and to provide openings of a size to receive the heads of animals to be fed from said pan.

15. In a chicken feeder, the combination with an upright receptacle and a feed pan therebeneath, of a cap for said receptacle provided with walls upwardly converging to a relatively narrow meeting portion, and a substantially flat plate mounted at the meeting portion of said cap, the cap being free to tilt to opposite sides of said meeting portion and being provided with apertures, and headed means connected with said cap and received through said apertures, whereby to provide a fulcrum for the oscillation of said plate, the plate having portions on each side of said apertures projecting over said walls of the top.

JOHN B. OLSON.
